US0D1018532S

(12) **United States Design Patent** (10) **Patent No.:** **US D1,018,532 S**
(45) **Date of Patent:** ** *Mar. 19, 2024

(54) **ELECTRONIC DEVICE**

(71) Applicant: **Samsung Electronics Co., Ltd.**, Suwon-si (KR)

(72) Inventors: **Jooho Seo**, Suwon-si (KR); **Donghun Kim**, Suwon-si (KR); **Jaehyuk Lee**, Suwon-si (KR)

(73) Assignee: **SAMSUNG ELECTRONICS CO., LTD.**, Suwon-si (KR)

(*) Notice: This patent is subject to a terminal disclaimer.

(**) Term: **15 Years**

(21) Appl. No.: **29/797,089**

(22) Filed: **Jun. 29, 2021**

(30) **Foreign Application Priority Data**

Dec. 30, 2020 (KR) 30-2020-0065948

(57) **CLAIM**

The ornamental design for an electronic device, as shown and described.

DESCRIPTION

FIG. 1 is a front perspective view of an electronic device showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is another front perspective view thereof, showing our new design in an alternative configuration.

The evenly-dashed broken lines in the drawings illustrate portions of the electronic device that form no part of the claimed design.

1 Claim, 8 Drawing Sheets
